UNITED STATES PATENT OFFICE.

EDWARD H. HEATH, OF HERINGTON, KANSAS.

GAME APPARATUS.

954,628.

Specification of Letters Patent. Patented Apr. 12, 1910.

Application filed June 18, 1909. Serial No. 503,006.

To all whom it may concern:

Be it known that I, EDWARD H. HEATH, a citizen of the United States, residing at Herington, in the county of Dickinson, State of Kansas, have invented certain new and useful Improvements in Game Apparatus; and I do hereby declare the following to be a full, clear, and exact description of the invention, such as will enable others skilled in the art to which it appertains to make and use the same.

This invention relates to game apparatus of the class wherein a game board is employed in connection with a plurality of balls and an instrument for shooting the balls to cause them to traverse the game board, and has for one of its objects to improve the construction and amuse and instruct the players and stimulate their skill and interest.

With this and other objects in view, the invention consists in certain novel features of construction as hereafter shown and described and then specifically pointed out in the claims, and in the drawings illustrative of the preferred embodiment of the invention, Figure 1 is a plan view of the improved device. Fig. 2 is a transverse section on the line 2—2 of Fig. 1. Fig. 3 is a diagonal section on the line 3—3 of Fig. 1, with all the balls but the cue ball removed from the center of the board. Fig. 4 is a view of the ball "shooting" implement partly in section.

The improved device comprises a board or base 10, preferably square and provided with a margin 11 entirely surrounding the board and projecting above the general surface of the same, as shown. The surface of the board is provided with four raised semi-circular portions 12—13—14—15, the semi-circular portions being less in length than the sides of the board so that vacant spaces 16—17—18—19 remain at the corners of the board, as shown. Formed in the upper face of each of the semi-circular members is a longitudinal recess 20 in which the balls with which the game is to be played are stored when not in use. Rising from the surface of the board within the spaces 16—17—18—19 are pegs 21, five pegs being arranged in each space and spaced at equal distances apart and likewise spaced from the corners of the board. Formed in each of the corner spaces 22 between the pegs 21 and the margin 11 of the board is a segmental shallow recess 22

to prevent the balls from rolling back after they have been "shot out".

A plurality of balls are provided, and represented at 37, and a shooting implement or "cue" device is likewise provided and constructed as illustrated in Fig. 4. This shooting implement comprises a tubular stock 38 having a longitudinal bore extending therethrough to slidably receive a rod 39 which forms the shooting member of the device. The stock 38 is also provided with a longitudinal slot 40 having lateral recess 41, and the rod 39 is provided with a pin 42 adapted to enter one of these recesses and support the rod in any required position within the stock. Secured to the inner end of the stock is a tubular handle member 43 into which the inner end of the rod 39 projects. The rod 39 is arranged to be spring-operated, so that it can be forcibly thrust forward to an extent equal to the range of the slot 40 and thus produce the "shooting" effect upon the balls. The spring element is preferably formed from an ordinary rubber band connected between the inner end of the stock 38 and the inner end of the rod 39, as shown. The handle member 43 is detachable from the stock 38, so that the rubber band spring may be readily renewed when worn or impaired.

By providing a plurality of notches 41 the pin 42 may be set in any one of the notches, and thus control the force of the "drive" imparted to the ball. Thus if the ball is to be driven with considerable force the rod 39 is moved inwardly and the pin 42 connected into the innermost notch, so as to set the rod at its inner point, and thus enable it to exert its greatest force upon the ball. The "shooting" is accomplished by the operator holding the stock 38 in one hand and releasing the pin 42 from the notch 41 with which it is for the time being engaged with the other hand, and thus releasing the spring and permitting the rod 39 to be actuated.

In a general way the game is played similar to "pool" and like games, and all the rules of such games may be made to apply. The game is played with balls, preferably hollow metal balls, and practically any number of balls may be employed, but generally from fifteen to twenty-five. The balls are numbered consecutively, and can be played by two or four persons, either partners or otherwise. Each player shoots from one of the corners, and the player who gets

the majority of balls or makes the highest score, counting the numbers on the balls, wins. Each player is provided with a cue ball, and preferably one of the shooters will 5 be provided for each of the players.

One of the games which it is possible to play upon the improved board is described as follows. After the players are seated around the board each facing one of the corners, each player is assigned a "cue" ball 10 distinctive from the other cue balls and distinctive from the playing balls so that it can be readily distinguished from them as for instance by being distinctively colored. The 15 designated number of playing balls are then placed in the center of the board and one of the players shoots his cue ball against one or more of the balls in the center of the board which propels and starts them moving. The 20 balls which roll out between the pegs at the corners and remain in the triangular space in the corners are considered "down" and are disposed in a designated place, for instance in one of the "racks" 20, by the 25 player, providing his cue ball remains on the board and does not also roll out between the pegs. The channel 22 serves as a stop to check the balls which may have been driven into the corner by the cue and to prevent them from rolling out too easily. If 30 his cue ball does not remain on the board he must stop playing and place the balls which were shot "down" by that shot, back on the board, and the next player shoots in 35 turn, the turn passing from the right to the left. If the first player shoots any balls "down" however the first player brings his cue ball back and shoots again from his corner, always shooting from about one inch in 40 front of the row of pegs at his corner. Each player retains the balls to which he is entitled after each shot and disposes them in the channels 20 and continues shooting until he misses, that is until he fails to shoot any ball 45 "down", or until his cue ball does not remain on the central portion of the board. Assuming that the number of playing balls is 17, when two are playing, the player first shooting "down" and placing nine balls in 50 his "rack" 20 wins the game. When three or more players participate, and do not play partners, the player wins who has the most balls in his "rack" after all the balls are shot "down." When four players participate and play partners the two players win 55 who first "rack" up nine balls.

It will be understood that a number of different games may be played similar to pool, and it is not desired to limit the device 60 to the playing of any specific form of game.

The board may be of any required size or

of any required material, but will preferably be of wood except the pegs 21 which will be of metal, and the whole board except the pegs may be papiér-maché or similar material or compound, and it is not desired therefore to limit the device of any specific material. The border 11 will preferably be extended to project at equal distances from each side of the base or body 65 portion, as shown, and the reverse side of the board may be adapted for playing another game if preferred. If preferred the border 11 may be of the same height as the semi-circular portions 12—13—14—15. The 70 pegs 21 are preferably covered with rubber or like material, as represented in Fig. 1.

What is claimed is:—

1. A game apparatus comprising a rectangular board having an inclosing elevated 80 margin, a flat central portion, a plurality of raised portions one at each side, and a plurality of pegs spaced apart and located in the corners of the board between the elevated side portions. 85

2. A game apparatus comprising a rectangular board having a flat central portion, a plurality of raised portions, one at each side, and a plurality of pegs spaced apart and located in the corners of the board 90 between the elevated side portions.

3. A game apparatus comprising a rectangular board having a flat central portion, a plurality of raised portions one at each side formed with curved inner edges, and 95 a plurality of pegs spaced apart and located in the corners of the board between the elevated side portions.

4. A game apparatus comprising a rectangular board having an inclosing elevated margin and a flat central portion, a plurality of raised portions one at each side formed with curved inner edges, and a plurality of pegs spaced apart and located in the corners of the board between the ele- 105 vated side portions.

5. A game apparatus comprising a rectangular board having an inclosing elevated margin and a flat central portion, a plurality of raised portions one at each side, 110 and a plurality of pegs spaced apart and located in the corners of the board between the elevated side portions, the surface of the board having depressions between the pegs and the inclosing margin. 115

In testimony whereof, I affix my signature, in presence of two witnesses.

EDWARD H. HEATH.
